UNITED STATES PATENT OFFICE

CHARLES B. JOHNSON, OF MILWAUKEE, WISCONSIN, ASSIGNOR TO GREAT LAKES GOLF CORPORATION, OF MILWAUKEE, WISCONSIN, A CORPORATION OF WISCONSIN

GOLF CLUB

Application filed March 9, 1928. Serial No. 260,518.

The invention relates to golf clubs and more particularly to means for re-enforcing the shaft-receiving portions of golf club heads.

5 An object of the invention is to re-enforce the shaft-receiving neck of a golf club head by means of a metal band or collar tightly and permanently fitting within a circumferential recess around the neck for preventing 10 cracking or splitting of the neck during the subsequent attachment of the shaft and later use of the club.

Another object of the invention is to surround the golf club neck with a tightly fitting 15 re-enforcing band which is molded into a circumferential recess formed around the neck.

A further object is to form the neck re-enforcing band by die casting metal around 20 the neck.

A further object is to re-enforce the reduced upper end of the neck by means of a wire serving or whipping having a band molded thereabout.

25 A further object is to protect and re-enforce the thin upper edge of the neck by a band molded about the upper portion of the neck and extending above the neck.

The invention further consists in the several features hereinafter set forth and more particularly defined by the annexed claims.

The accompanying drawing illustrates a fragmentary portion of a golf club embodying the invention, parts being broken away 35 and parts being shown in longitudinal section.

In the drawing, the numeral 10 designates the head of a driver which may be, as usual, of wood and is provided with a tapering neck 40 11 through which extends a tapered shaft-receiving bore 12 having its larger diameter at the upper end of the neck and its smaller end opening at the bottom surface of the head.

45 An annular groove or channel 13 is formed

about the club head neck 11, preferably adjacent the lower end portion of the neck. The annular groove 13 receives therein a re-enforcing band or collar 14 which fills the groove to tightly engage the bottom and side 50 walls thereof, and the outer surface of the band 14 is preferably flush with the exterior surface of the neck. The band 14 is cast or molded in place into the groove 13 and is preferably formed of metal introduced into 55 the groove by a die casting operation. The metal employed for this purpose is preferably an alloy of suitable tensile strength, and it is found in practice that the die casting can be accomplished without charring the 60 wood. The bottom wall of the groove may have indentations 15 formed therein to receive the die cast metal and thereby lock the band in place against turning. These indentations may be omitted however, since a 65 slightly rough surface of the bottom wall of the groove or a slightly oval shape of the bottom wall will accomplish the same purpose. The cast metal band 14 on cooling contracts and places the tubular wooden neck 70 11 under compression, thereby preventing cracking or splitting of the neck. The exterior surface of the band 14 may be finished in any suitable manner to provide a neat 75 appearance, and preferably the band contrasts in appearance with the adjacent finished surface of the wood.

In the event that a pre-formed metal band is to be used, the band may be inlaid into the annular groove about the neck by a pressing 80 or squeezing operation, this operation serving to fill the groove with the metal and also placing the metal band under peripheral tension to tightly encircle the neck. It is also possible to form the re-enforcing band 85 14 by molding bakelite into the annular groove about the neck, but this material is not so satisfactory for this purpose as metal.

The tapered neck 11 of the club head is provided with a reduced upper end portion 16 90

terminating at a comparatively thin upper edge, and the lower end of the reduced end portion 16 is defined by an annular shoulder 17. A wire serving or whipping 18 is tightly wound about the reduced upper end portion 16 of the neck and extends between the shoulder 17 and the thin upper edge of the neck.

A re-enforcing band or sleeve 19 is placed over the whipping 18 in engagement therewith, and extends from the shoulder 17 which it tightly engages to a point above the thin upper edge of the neck. The band 19 lies flush with the tapered outer surface of the club head neck 11 and forms a continuation 15 of this outer surface, while the inner surface of the band above the upper edge of the shank forms a continuation of the walls of the bore 12 in the neck. The band or sleeve 19 is molded in place and is preferably 20 formed of metal which is die cast about the upper end portion of the neck. In the casting operation the metal enters the interstices of the wire whipping 18, serving to hold both the band and whipping firmly in place. The 25 cast metal band 19 on cooling contracts and places the wood in the thin upper end of the tubular neck under compression to prevent cracking or splitting of the neck. The exterior surface of the band 19 may be finished in any suitable manner.

In assembling the golf club, the hollow tapered neck of the club head has fitted thereon the bands 14 and 19. The lower tapered end portion of a tubular metal shaft 20 is received within the tapered bore 12 in the club head neck 11 to tightly engage the walls thereof, and also fits tightly within the thin upper portions of the band 19. A wooden plug 21 is received within the lower end of 35 the tubular shaft to tightly engage the walls thereof, and the upper end of the plug preferably extends beyond the plane of the band 14. An attaching screw 22 is threaded into the heel portion of the head to pass transversely through the tubular shaft 20 and 40 through the wooden plug 21 therewithin, and serves to retain the shaft in its tightly fitting relation within the neck 11 against relative rotation. The lower ends of the shaft and 45 plug are then cut on a bias to lie flush with the bottom surface of the club head. Another screw 23 is threaded into the lower end of the plug 21 and passes through a wall of the shaft 20 to enter into the club head.

50 By means of this invention, the neck of the golf club head is re-enforced in a simple and effective manner to prevent splitting or cracking of the neck and thereby insure a permanently tight connection between the 55 club head and its shaft. The invention further provides a means whereby the neck of the club head may be finished in a neat and expeditious manner.

55 What I claim as new and desire to secure by Letters Patent is:

1. A golf club comprising a head having a shaft-receiving neck, a whipping surrounding said neck, and a re-enforcing band molded onto said whipping to surround said neck.

2. A golf club comprising a head having a shaft-receiving neck, a metal whipping surrounding said neck, and a metal band cast about said neck to surround and engage said whipping.

70 In testimony whereof, I affix my signature. 75
CHARLES B. JOHNSON.
